AERIAL MULTIMINE

Erich Bickel, Baden, near Zurich, Switzerland

Application October 31, 1938, Serial No. 237,952
In Switzerland March 18, 1937

5 Claims. (Class 102—29)

The present invention relates to a modification of the air defense system which forms the subject matter of my copending application Ser. No. 166,921, filed Oct. 2, 1937. The projectiles according to the present invention contain a plurality of individual aerial mines which may be laid out simultaneously or consecutively. Each individual mine comprises a mine proper, a carrier, for example, a parachute, and a long, thin flexible member, such as a wire, interconnecting the carrier and the mine proper.

In the case of projectiles containing one mine only such as disclosed in my copending applications Ser. No. 166,921 and Ser. No. —— and being designed to be shot extremely high and therefore being of large caliber, there is much space available in the projectile and if this space is used up the wire spool is large and the wire is several miles long. Although the long wires produce large barrages, their unwinding and laying out takes considerable time what is in many cases not desirable. On the other hand, there are cases where the quick laying out of a curtain of considerable width is desired. For such conditions the multi-mine according to the present invention is the answer.

As said above, the projectiles according to the present invention may be constructed to lay out a plurality of individual mines simultaneously or one after the other. In the former case the individual mines are arranged in the projectile as a bundle, i. e. are located around the axis of the projectile, and in the latter case they are piled up on top of one another. In the former case the mines are laid out at the same elevation above the ground and the curtain or barrage has the form of a cylinder of circular or elliptic cross section. In the latter case the individual carriers are dotted in the air along the path of the projectile and the wires with the mines hang down therefrom in a plane. In the former case a protective curtain can quickly be produced around the object to be protected, for example, a battle ship, an airport, an ammunition plant, etc. In the latter case a long stretched curtain along the paths of the projectiles which paths in this case may be held rather flat can be produced quickly to form a barrage for shielding long stretched objects, for example, roads crowded with marching troops, stationary defense lines, etc.

In the drawings:

Figure 1 is a longitudinal sectional view of a bundle multi-mine according to the present invention.

Figure 2 is a cross section of the mine shown in Fig. 1 and taken along line 2—2.

Figure 3 is a longitudinal sectional view of a modified multi-mine according to the present invention.

Figure 4 is a cross sectional view of the mine shown in Fig. 3 and taken along line 4—4 in Fig. 3.

Figure 5 is a diagrammatic showing of a phase 10 of the laying out operation of a multi-mine according to Figs. 1 and 2.

Figure 6 is a diagrammatic illustration of another phase of the laying out of one individual mine of a multi-mine according to the present 15 invention.

Figure 7 is a diagrammatic showing of a mine barrage formed by a multi-mine as shown in Figs. 1 and 2.

Figure 8 is a phase of the laying out operation 20 of the modified multi-mine shown in Figs. 3 and 4.

Figure 9 is another phase of the laying out operation of the modified mine shown in Figs. 3 and 4.

Figure 10 is a diagrammatic showing of an air 25 defense curtain produced by the modified mine according to Figs. 3 and 4 whereby the path of the projectile is substantially flat.

Figure 11 is a diagrammatic showing of an air 30 defense curtain produced by the modified mine according to Figs. 3 and 4 whereby the path of the projectile is substantially steep.

Like parts are designated by like numerals in all figures of the drawings.

The projectile illustrated in Figs. 1 and 2 contains five individual mines. 1 designates a conventional time fuse, 2 is the body member of the projectile into which the fuse is inserted, and 3 is the shell which may be pressed on to the body member 2. 4 is an individual mine which is shown in elevation at the right and in section at the left side of Fig. 1. 5 diagrammatically shows an impact detonator which is not shown in detail as such detonators per se are not subject of the present invention. 6 is the mine proper with the destructive charge; 7 is the wire spool which, in the embodiment of the invention shown, surrounds the mine proper; 8 is a capsule which contains the folded up parachute 9. By the provision of slots 14 capsule 8 is made to open resiliently unless held together for purposes to be described later. From the bottom of the shell 3 a piston or trunk part 10 extends into the interior of the projectile and into a suitable cavity or bore of the stem part 11 which extends from

the body member 2 into the interior of shell 3. The stem 11 contains the dismembering charge 12 which is connected with and actuated by the time fuse 1 by means of a fuse 13 which is also located in the stem 11. When the charge 12 is exploded the resulting gas pressure separates the shell part 3 from the body member 2 whereby the projectile is dismembered and laying out of the individual mines is started.

Due to centrifugal forces caused by the rotation of the projectile, which rotation is produced by the rifling of the gun, the individual mines 4 separate themselves following an outward moving spiral path. This phase of the laying out operation is shown in Fig. 5 of the drawings. The body 2 with the stem 11 and the shell 3 follow for some more time the direction of the original path of the projectile and then fall to the ground.

At first the individual mines remain in compact condition in which the cups or capsules 8 are held together and to the wire spools 7 by means of slow burning time fuses 15 which fuses are wound around the upper rims of the capsules and which fuses are connected for ignition with the charge 12 by means of channels 16 in stem 11. The end of the fuse 15 which extends into the channel 16 is ignited as soon as the charge 12 is ignited. When the fuse 15 is completely burnt the cup 8 opens somewhat and disconnects it from wire spool 7. Due to increased air friction the cup is removed from the parachute 9 which is then free to unfold. The mine 6 with the coiled wire keeps on moving whereby, due to the retarding action of the parachute, the wire is unwound from the spool and stretched out. This phase of the laying out operation is shown in Figure 6. Finally, the mine proper 6 drops down bringing the wire 1 into substantially vertical position. Figure 7 is a diagrammatic showing of a fully laid out multimine having five individual aerial mines.

Figures 3 and 4 show a projectile in which the individual mines are not bundled but piled on top of each other. The projectile shown, by way of example, contains four mines whereby the foremost forms the projectile body. The individual mines consist of the mines proper 17, 18, 19 and 20, the last forming the head piece of the projectile. Each mine proper is connected individually with one end of a coiled up wire 21, 22, 23 and 24 respectively, the other end of which is connected with a parachute 25, 26, 27 and 28 respectively. Stem 29 extends from the head 20 through the center of the projectile and the individual mines are strung on said stem. The parachutes are individually folded into pan shaped capsules 30, 31, 32 and 33 respectively to which pans the parachutes may be fastened and which pans are provided with openings for accommodation of the stem 29. The three lower pans have annular grooves 34, 35 and 36 respectively into which about one annular half of a radially split resilient ring 37, 38 and 39 is inserted respectively. The other half of said ring rests in annular grooves provided in the stem 29. The individual mines are thereby held in position with respect to the stem.

Laying out of the mine takes place as follows:

At a predetermined moment the time fuse 1 ignites the fuse 40 which extends through the stem down to the separating charge 41 and ignites the latter. The resulting gas pressure pulls off the shell. Thereby the bottom mine 17 is freed and due to air friction removed from stem 29 pulling the wire 21 from its spool. For the

present, the other mines remain on the stem. This phase of the laying out operation is diagrammatically shown in Fig. 8. After wire 21 is completely unwound the parachute 25 is pulled from the stem with and out of its capsule 30. Under the influence of the air current the parachute unfolds.

As soon as capsule 30 is pulled from the stem 29, the spring ring 37 is freed and snaps out of engagement with the stem 29. Then the next mine 18, 22, 26 is freed and unfolded in the same manner as was mine 17, 21, 25. Thereafter the mine 19, 23, 27 is unfolded. The top mine 28, 24, 20 unfolds in reverse manner, i. e. at first the parachute 28 is unfolded, then the wire 24 is unwound because of its own inertia and the forward movement of member 2, 20 whereafter the mine proper 20 stretches the wire out completely. Since the last mine is laid out along the descending path of the projectile it is right away in correct position. Figure 9 shows an intermediate phase of the laying out operation.

Figure 10 diagrammatically illustrates the curtain laid out by means of a projectile following a flat path and Fig. 11, the curtain laid out by means of a projectile shot up to follow a steep path. In Figs. 8 to 11 the path of the projectile is shown in dotted lines; the dash and dot line in Figs. 9 to 11 indicates the position of the parachutes.

The mines proper 6 and 17 to 20 are provided with impact detonators, for example as shown in my copending application Ser. No. — filed

While I believe the above described embodiments of my invention to be preferred embodiments, I wish it to be understood that I do not desire to be limited to the exact details of design and construction shown and described, for obvious modifications will occur to a person skilled in the art.

I claim:

1. An air defense device comprising a projectile having a shell and a substantially pointed head-piece, a stem member rigidly connected with said head-piece and centrally extending into said shell, a plurality of individual air mines, each mine consisting of a mine proper, a parachute and a wire wound into a solid spool and interconnecting said mine proper and said parachute, said mines being disposed within said shell and around said stem member, and a separating charge disposed between said mines for separating said shell from said mines and said mines from one another and from said stem member.

2. An air defense device comprising a projectile having a shell including a closed bottom portion and an open top, a substantially pointed head-piece for closing the open top of said shell having a substantial, rigid and permanent stem portion extending centrally into said shell, a plurality of individual air mines disposed within said shell and around said stem portion, each mine consisting of a mine proper, a folded parachute, and a long and thin wire connected to and interconnecting said mine proper and said parachute and being tightly wound into a compact spool body adapted to remain a compact spool body from which the wire is gradually pulled off while said body moves through the air by its own inertia after disassembly of the projectile in the air, and a bursting charge disposed substantially at the end of said stem portion and inside said bottom portion for separating said shell from said mines and liberating said mines.

3. An air defense device comprising a projectile including a shell having a bottom portion and an open top, a head piece for closing the open top of said shell having a stem member extending centrally into said shell and having a flared out end portion fitting into said bottom portion, a plurality of individual air mines disposed within said shell and around said stem member between said head piece and said flared out end portion, each mine comprising a mine proper having a longitudinal conical outside configuration, the large diameter end of said mine proper being located adjacent to said head piece, a long and thin wire connected at one end with said mine proper and tightly wound around said mine proper and forming a solid spool body of substantially cylindrical outside configuration, and a parachute connected with the other end of said wire and being folded up and disposed in line with and adjacent to that end of said spool body which is wound around the small diameter end of said mine proper, and a bursting charge disposed substantially at the end of said stem member and between said end and the interior bottom portion of said shell for separating said shell from said stem member and liberating said air mines.

4. An air defense device comprising a projectile including a shell having a closed bottom portion and an open top, a head piece for closing the open top of said shell having a stem member extending centrally into said shell, a plurality of individual air mines disposed within said shell and around said stem member, each mine comprising a mine proper having a longitudinal conical outside configuration, the large diameter end of said mine proper being located adjacent to said head piece, a long and thin wire connected at one end with said mine proper and being tightly wound around said mine proper and forming a solid spool body of substantially cylindrical outside configuration, a parachute connected with the other end of said wire and being folded up and disposed in line with and adjacent to that end of said spool body which is wound around the small diameter end of said mine proper, and

a resiliently self-opening container member enveloping said folded parachute and tightly fitting between said stem member and said shell, and a bursting charge disposed inside of the end portion of said stem member and between the bottom portion of said shell and said stem member for separating said shell from said stem member and liberating said air mines and said container members.

5. An air defense device comprising a projectile including a shell having a bottom portion and an open top, a head piece for closing the open top of said shell having a stem member extending centrally into said shell, a plurality of individual air mines disposed within said shell and around said stem member, each mine comprising a mine proper having a longitudinal conical outside configuration, the large diameter end of said mine proper being located adjacent to said head piece, a long and thin wire connected at one end with said mine proper and being tightly wound around said mine proper and forming a solid spool body of substantially cylindrical outside configuration, a parachute connected with the other end of said wire and being folded up and disposed in line with and adjacent to that end of said spool body which is wound around the small diameter end of said mine proper, a resiliently self-opening container member surrounding the end portion of said spool body wound around the small diameter end of said mine proper and also surrounding said folded parachute, a bursting charge disposed inside the end portion of said stem member and between said stem member and the inside of said bottom portion for separating said shell from said stem member and liberating said air mines, and time fuses connected for ignition with said bursting charge and individually wound around said container members for individually tightly holding said container members to said spool bodies and to said folded parachutes and for individually setting said container members free for opening and said spool bodies free for unfolding as soon as said fuses are burnt.

ERICH BICKEL.
